E. Page,

Molasses Pitcher,

No 13,400,

Patented Aug. 7, 1855.

UNITED STATES PATENT OFFICE.

EDWARD PAGE, OF WORCESTER, MASSACHUSETTS.

MOLASSES-PITCHER.

Specification of Letters Patent No. 13,400, dated August 7, 1855.

To all whom it may concern:

Be it known that I, EDWARD PAGE, of Worcester, in the county of Worcester and State of Massachusetts, have invented a new 5 and Improved Mode of Catching Molasses which Drips from a Molasses-Cup; and I do hereby declare that the following is a full and exact description thereof.

I cause the band B in the accompanying 10 drawings to clasp the cup c to which the hook H is fastened. On this hook the vessel v is suspended. When the molasses cup c is in an upright position the vessel v will 15 catch the molasses which drips when the cup c is used in pouring out molasses. The ves-

sel v will swing self acting on the hook H and remain nearly upright. The vessel v can be taken from the hook H and cleaned when necessary.

What I claim as my invention and desire 20 to secure by Letters Patent is—

The application to molasses cups of a vessel to catch the molasses which drips from the cup and the vessel to swing as herein described.

EDWARD PAGE.
